(57) **CLAIM**

The ornamental design for a ground fault circuit interrupter with electric arc protection, as shown and described.

DESCRIPTION

FIG. 1 is a front view of a ground fault circuit interrupter with electric arc protection showing my new design;
FIG. 2 is a right side elevational view thereof;
FIG. 3 is a back side elevational view thereof;
FIG. 4 is a left side elevational view thereof;
FIG. 5 is a top plan view thereof; and,
FIG. 6 is a bottom view thereof.
